UNITED STATES PATENT OFFICE

JOHN PURCELL, OF CHICAGO, ILLINOIS

WHEEL HUB WEAR PLATE

Application filed December 6, 1930. Serial No. 500,542.

My invention relates to wear or liner plates adapted to be applied intermediate of the hubs of the wheels and the hub faces of the journal boxes of locomotives and railroad cars for the purpose of protecting the opposing faces of the wheel-hub and of the journal box against wear.

My invention also has for its object the provision of a wear plate whereby heat generated by the frictional contact encountered during movement of the locomotive or car will be dissipated or rapidly radiated to the atmosphere, thereby preventing the wheel-hubs and journal or driving boxes becoming excessively hot.

The objects and advantages of my invention will be readily comprehended from the following detailed description of the accompanying drawings, wherein—

Figure 1 is a vertical sectional view of a locomotive driving wheel and driving or journal box, with my improved wear plate shown applied to the wheel.

Figure 2 is an enlarged sectional elevation, the view being taken substantially on the line 2—2 of Figure 1, as viewed by the arrows.

Figure 3 is an enlarged sectional view taken substantially along the off-set line 3—3 of Figure 2, looking in the direction of the arrows.

Figure 4 is an enlarged detail sectional view, taken on the line 4—4 of Figure 2 looking in the direction of the arrows.

Figure 5 is a view similar to Figure 1 showing the application of my improved wear plate to a truck wheel of the inside bearing type.

Figure 6 is an enlarged sectional elevation taken substantially on the line 6—6 of Figure 5, looking in the direction of the arrows.

Figures 7 and 8 are, respectively, perspective views of the two segments of my wear plate as formed for mounted wheels of the inside bearing type.

Figure 9 is a sectional view of a wheel of the outside bearing type and provided with my improved wear plate.

Figure 10 is a sectional view similar to Figure 3, illustrating a modified form.

My improved wear plate is preferably in the form of an annular member or ring of a diameter substantially equal to the diameter of the side face of the hub of the wheel and in the exemplifications disclosed in the first eight figures of the drawings is shown made in segments in order to permit application to be made to assembled trucks with wheels of the inside bearing type.

In Figure 1, my improved wear plate is shown applied to a locomotive driving wheel hub indicated at 15, secured to a journal of which a portion is shown at 16, which is journaled in the usual drive or journal-box 17.

Considerable wear on the hubs of wheels is encountered during operation due to the frictional contact between the wheel-hubs and the journal-boxes, especially where the tracks have sharp and frequent curves. Such frictional contact not only results in rapid wear, but also in excessive heating of the hubs of the wheels and of the journal-boxes.

Where my improved wear plate is to be applied to a wheel before it is mounted, or to a wheel of the outside bearing type, it consists preferably of an annular plate or ring 18 of diameter substantially equal to the diameter of the hub face disposed toward the journal-box. The plate 18 is provided centrally with a hole slightly larger than the diameter of the journal 16, so as to provide a space between the inner periphery of the plate and the journal, as shown at 19.

Where my improved wear plate is intended for application to mounted wheels of the inside bearing type as shown in Figures 1 and 5, the plate may be made in two half segments or sections 18^a and 18^b, as shown in Figures 7 and 8. Or the plate 18, after being machined to suit the particular application or wheel, is split along the line indicated at 20 in Figure 2, and the abutting edges of the segments given a slight bevel as shown at 21 in Figures 7 and 8 in order to provide a better welding joint as shown at 22 in Figure 4. This enables each half segment to be separately applied to the wheel-hub and fitted about the axle or journal.

As one object of my invention is the provision of an air space between the wear plate

and the wheel-hub to which it is attached, I provide means for maintaining a spaced relation between the plate and the object to which it is attached.

- 5 In the specific exemplification of the invention, this means preferably consists of a number of integral projections or bosses 23 on the side of the plate which is intended to be disposed toward the wheel-hub to which it is to be attached. In order to properly maintain the proper spacing throughout, a number of bosses 23 are provided and spaced equal distances apart circumferentially about the plate as shown in dotted lines in Figure 2 and 10 preferably in a circumferential plane centrally between the outer and inner peripheries of the plate as shown.
- 15 In order to assist in maintaining the proper position of the plate 18 or the plate segments 20 18^a and 18^b, I prefer to provide the side face of the wheel-hub 15 with a corresponding number of recesses adapted to snugly receive the respective bosses 23, as shown at 24 in Figures 1 and 3; or these recesses 24 may be 25 made continuous so as to provide an annular groove of width sufficient to snugly receive the bosses 23. It will be understood, however, that the recesses 24, or groove, are of a depth less than the thickness of the bosses so 30 that the latter are only partially embedded in the recesses, as shown in Figures 1 and 3.

The plate and each boss is provided with a hole therethrough with the outer or plate side of the holes preferably flared as shown at 25, 35 see Figure 3, and one side of the flared portion of each hole 25 preferably provided with a small groove as at 26, and shown in dotted lines in Figure 2. The wheel-hub side face, at points registering with the holes in the 40 bosses, is provided with threaded holes adapted to receive the threaded ends of the screw-plugs 27. After the plugs 27 have been firmly screwed into the threaded holes and caused to bottom therein, the outer plain end of each 45 plug is then riveted or upset so as to completely fill the countersunk or flared hole, causing a portion of the riveted or upset end of the plug to enter the groove 26, thereby effectively locking the screw-plug against unscrewing; while the outer ends of the plugs 50 are caused to be flush with the outer face of the plate 18.

While I prefer to partially embed the bosses in recesses as described, if desired, the recess may be omitted and the bosses made to bear directly against the flat face of the wheel-hub, as shown at 23^a in Figure 10.

The original shape or condition of the screw-plugs 27 is shown in dotted lines in 60 Figures 3 and 10; that is to say the outer ends of the screw-plugs are shown before being riveted over or upset as heretofore described.

I also prefer to provide the hub facing 65 side of the wear plate 18 with a series of

smaller projections or bosses 28, located preferably near to the outer periphery of the plate and at equally spaced points disposed in planes intermediate of the larger attaching bosses 23, as more clearly shown in Figures 2, 6, 7 and 8.

These projections 28 preferably also bear against the hub face of the wheel and supplement the bosses 23 in the function of supporting the wear plate to maintain an air space between the plate and the wheel hub face.

In Figure 5, I show the application of my improved plate to the hub of the wheel 29 of the inside bearing type, namely with the journal box 30 located on the inner side of the wheel about the journal 31. Except for size or diameter, the plate 18 is identical with that heretofore described; and in view of the fact that it is shown in connection with an inside bearing type of wheel and to permit application after the assembly of a journal and the wheel, the plate has been shown consisting of the two half segments 18^a and 18^b preferably welded together at the points 22 as previously described.

In this application, like in the application to the locomotive drive wheel, the plate has been shown applied to the hub of the wheel, by providing the hub face either with a continuous annular recess or with a series of recesses adapted to partially receive the outer ends of the bosses 23; the bottoms of the recesses having threaded holes to receive the threaded ends of the screw plugs 27 all as heretofore stated.

In Figure 9, I show the application of my improved plate to the outer hub face of a wheel 32 of the outside bearing type, namely a type where the journal 33 extends through the hub of the wheel into the outside journal box 34. The wear plate 18 for applications of this type may be made continuous as previously stated, being of the same construction as heretofore described, with its attaching bosses 23 preferably partially inserted in the face of the wheel hub and apertured to receive the screw plugs 27 whose outer ends are upset or riveted as heretofore described in order that they may come flush with the outer face of the plate 18.

The plates in the applications shown in Figures 5 and 9, it will be understood, are in every respect similar to the construction of the plate as described in connection with the application to a locomotive drive wheel as shown in Figures 1 to 3, inclusive.

My improved wear plate may be made of any suitable material adapted to provide the best anti-friction characteristics; and it will be understood that in all instances the bore or inner periphery of the plate is preferably of a diameter somewhat larger than the diameter of the axle or journal in connection with which it is to be used, in order to pro-

vide the circumferential air admitting space 19 heretofore referred to.

With my improved plate secured in place, air is permitted to flow through the circumferential opening 19 into the space intermediate of the plate and the hub of the wheel; the flow or more or less rapid circulation of air being induced by the rapidly revolving movement of the bosses or spacer elements, which impart a revolving motion to the air. This movement of the air causes it to move out radially from between the plate and the hub face which in turn induces a flow of air through the space 19. This constant radial movement or outward flow of air tends to cool the plate as well as the hub of the wheel by constantly carrying away the heat, which may be generated in the plate due to its frictional contact with the hub face of the journal box, and thus prevents the heat being imparted to the hub of the wheel.

It is also apparent that with the plate rigidly secured to the wheel hub, a running bearing for the hub face of the journal box is provided and consequently the effects of friction and wear are sustained by the plate and not by the hub of the wheel.

As a result, the wear or damage resulting from the frictional contact is sustained by a less expensive part or element of the running gear, namely by a part which can be more readily removed and renewed without loss of a more expensive wheel and without necessity of dismantling the running gear of a rail-road car or of the drive wheels of a locomotive. In providing my improved plate with the spaced apart air whipping projections or bosses, a rapid dissipation of heat generated is induced while excessive heating of the wheel hubs and journal boxes is prevented.

It will be understood, however, that if desired, my improved wear plate may be attached to the hub face of the journal box; the bosses of the plate maintaining a spaced relation between the plate and the journal box hub face so as to permit circulation of air therebetween.

Although I have described what I believe to be the simplest embodiments of my invention, in terms employed merely as terms of description and not as terms of limitation, structural modifications may be made without, however, departing from the spirit of my invention.

What I claim is:

1. A wear plate of the character described provided with a central opening for passage of a wheel journal therethrough, said opening being of a diameter larger than the diameter of the journal so as to provide an annular air space, the attaching side of the plate being provided with spaced apertured bosses adapted to maintain the plate in fixed spaced relation with the element to which it is secured, and means disposed through the plate

and the apertures in the bosses for securing the plate in place.

2. A wear plate of the character described provided with a central opening adapted for passage of a wheel journal therethrough, the plate at its central opening being formed to permit flow of air about opposite faces of the plate, the attaching side of the plate being provided with projecting portions for maintaining the plate in spaced relation with the element to which it is secured, said projecting portions being formed to permit flow of air thereabout, certain of said projecting portions being apertured to receive means for securing the plate in place.

3. A wear plate of the character described provided with a central opening for passage of a wheel journal therethrough, said opening being of larger diameter than the diameter of the journal to permit air circulation therethrough, means arranged on the attaching side of the plate for maintaining the plate in spaced relation with the element to which the plate is to be secured, said plate being provided with flared apertures adapted to receive means for securing the plate in place and permit said means to extend flush with the outer face of the plate.

4. A wear plate of the character described provided with a central opening adapted for passage of a wheel journal therethrough, said opening being of a diameter larger than the diameter of the journal so as to provide a circumferential air space between the plate and journal, means arranged on the attaching side of the plate whereby the plate is maintained in spaced relation with the element to which it is secured, said means being arranged to permit free passage of air.

5. A wear plate of the character described provided with a central opening adapted for passage of a wheel journal therethrough, said opening being of a diameter larger than the diameter of the journal so as to provide an annular space between the plate and journal, one face of the plate, at circumferential points intermediate of its inner and outer perimeters, being provided with spaced apart apertured attaching bosses and with spaced apart bosses arranged circumferentially adjacent to the outer perimeter of the plate and disposed at points intermediate of the first mentioned bosses, and means disposed through the apertured bosses for securing the plate in place.

6. A wear plate of the character described comprising a plate of predetermined dimensions to fit between a wheel-hub and the adjacent side of a journal-box and provided with an opening for passage of a wheel journal therethrough, the opening being of larger diameter than the diameter of the journal to permit air circulation therethrough, said plate on its attaching face having a plurality of protruding portions arranged in spaced

relation whereby the plate is held in spaced relation with the element to which it is secured, and circulation of air thereabout permitted, the plate being provided with screw-plug receiving apertures whose outer ends are countersunk and provided with grooves whereby the outer ends of the screw-plugs may be riveted and portions of the upset plug metal caused to enter the grooves.

- 10 7. A wear plate of the character described comprising a plate of predetermined dimensions to fit between a wheel-hub and a journal-box and provided with an opening for passage of a wheel journal therethrough and of larger diameter than the diameter of the journal to permit air circulation, the attaching face of the plate being provided with a plurality of spaced bosses arranged circumferentially on said face, with certain of said bosses being apertured to receive screw-plugs and the outer ends of the apertures enlarged in a non-circular manner whereby the outer ends of the screw-plugs may be riveted flush with the face of the plate and locked against rotation.

8. A wear plate of the character described comprising a plate of predetermined dimensions to fit between a wheel-hub and a journal-box and provided with an opening for passage of a wheel journal therethrough and of larger diameter than the diameter of the journal to permit air circulation therethrough, the attaching face of the plate being provided with a plurality of circumferentially spaced bosses, certain of said bosses having screw-plug receiving apertures enlarged at the outer ends in a non-circular manner, the element to which the plate is to be attached being provided with sockets of depth less than the length of the apertured bosses and adapted to receive the ends of said bosses, with threaded holes in the bottoms of said sockets; and screw-plugs adapted to pass through the apertured bosses and to screw into the threaded holes, the outer ends of the screw-plugs being riveted flush with the face of the plate and so as to fill the enlarged outer ends of the apertures in said bosses.

JOHN PURCELL.
